(57) **CLAIM**

The ornamental design for a solar charger for doorbell as shown and described.

DESCRIPTION

FIG. 1 is a front and left side perspective view of a solar charger for doorbell, showing my design.

FIG. 2 is a rear and right side perspective view thereof;

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front and left side perspective view thereof, showing the solar panel in an alternative position; and,

FIG. 10 is a rear and right side perspective view of FIG. 9. The figures include broken, solid and dash-dot-dash lines. The dash-dot-dash lines illustrate an unclaimed boundary of the claimed design. The broken lines in the drawings depict portions of the solar charger for doorbell that form no part of the claimed design.
